UNITED STATES PATENT OFFICE.

ELLA O'REGAN, OF LOUISVILLE, KENTUCKY.

DESIGN FOR A SKIRT.

SPECIFICATION forming part of Design No. 32,604, dated April 24, 1900.

Application filed February 10, 1900. Serial No. 4,824. Term of patent 7 years.

To all whom it may concern:

Be it known that I, ELLA O'REGAN, a citizen of the United States, residing at Louisville, in the county of Jefferson and State of Kentucky, have invented and produced a new and useful Design for a Skirt, of which the following is a specification, reference being had to the accompanying drawing, forming part of this specification, and in which is shown a skirt embodying my new design.

As shown in the drawing, the main feature of my design consists in an open or finely-reticulated body portion A, upon which are diagonally arranged intersecting strips B, which subdivide the body portion into diamond-shaped panels C. At the top of the

reticulated portion is a plain strip D, at the top of which is a narrow band E. At the bottom of the reticulated portion is a narrow ornamental reticulated border F, between which and the main portion is a narrow strip G, similar to the strips B.

Having thus fully described my invention, what I claim as new, and desire to secure by Letters Patent, is—

The design for a skirt, as herein shown and described.

ELLA O'REGAN.
